CLIP FOR HAIR WAVING APPARATUS

Herman C. Schlicker, Brooklyn, N. Y., assignor to
 Clairol, Inc., New York, N. Y., a corporation of
 New York

Application December 11, 1940, Serial No. 369,575

4 Claims. (Cl. 132—31)

This invention relates to devices for making a permanent wave or curl in human hair, and more particularly to an improved clip for use with such devices.

The clip of the invention is designed for hair waving equipment and comprises a mandrel about which a part of the hair is wound, and a heating pad for enclosing the curled hair. The clip is used to compress the heating pad on the hair for the waving process. A laminated waterproof wrapper lined internally with absorbent material is included in the combination to prevent moisture from harming the clip.

In accordance with the invention, the improved hair clip is comprised essentially of three sections, namely a center bridge and two jaws hingedly connected with the bridge. The jaws are arranged to clamp the heating pad more evenly and securely against the wound hair. Moreover, the leverage from the center bridge to the lower end of the jaws is made relatively short whereby less spring tension is required to accomplish the necessary clamping action. Also, the jaw pressure at the neck of a hair section being treated is more direct than in prior devices, resulting in greater stability of operation.

The springs for urging the jaws towards each other in the clip of the invention need not be as strong as in prior devices, thus facilitating handling of the clip. The improved clip also comprises a flat spring interposed between the finger plates for manipulating the jaws. This flat spring may be either U-shaped or W-shaped, and prevents complete collapse of the jaws when the device is not being used.

It is accordingly an object of the invention to provide an improved three-section clip with a center bridge and two jaws hingedly connected therewith.

Another object of the invention is to provide an improved hair clip requiring less spring tension than prior devices; that will uniformly and securely press the heating pad against hair wound on a mandrel; and that is stable in operation.

Still another object of the invention is to provide an improved clip of the character referred to which is provided with a flat spring to prevent complete collapse of the jaws.

These and further objects of the invention will become more evident in the following description of preferred embodiments of the invention illustrated in the drawings, wherein:

Fig. 1 is a view in perspective of my improved hair clip.

Fig. 2 is a cross-sectional view of the clip of Fig. 1 on an enlarged scale, the clip being shown in connection with a complete hair waving equipment.

Fig. 3 is a side elevational view of the hair clip of Fig. 1.

Fig. 4 is a top view of the clip.

Fig. 5 is a perspective view of another embodiment of the invention.

Fig. 6 is an end view, on an enlarged scale of the clip of Fig. 5 with some parts broken away.

Referring to the drawings and more particularly to Figs 1 to 4, my improved hair clip comprises a curved center bridge 10. Two arcuate

15 jaws 11 and 12 are hingedly connected with the center bridge 10 on pins 13 and 14. Two handles or finger plates 15 and 16 serve to manipulate jaws 11 and 12. Finger plates 15 and 16 may be of Bakelite or other suitable material. Jaw

19 11 comprises an upwardly extending portion 17 secured to finger plate 15 by a suitable screw or rivet 18. Jaw 12 comprises a similar upwardly extending portion 20 similarly secured by a screw or rivet to finger plate 16.

25 A coil spring 24 embraces hinge pin 13. One free end 25 of coil spring 24 presses against jaw 11, while the other free end 26 thereof presses against center bridge 10. Similarly a coil spring 27 is provided with two free ends 30 and 31.

30 Spring end 30 presses against jaw 12, while free end 31 presses against center bridge 10.

A W-shaped flat spring 32 is arranged between the two finger plates 15 and 16, and is secured thereto by rivets 33. Coil springs 24 and 27

35 serve to urge the free ends of jaws 11 and 12 towards each other, while flat W-shaped spring 32 partly counteracts the spring pressure of coil springs 24 and 27. Flat W-shaped spring 32 is

designed to prevent the complete collapse of jaws 40 11 and 12 when no pressure is applied on finger plates 15 and 16. Jaws 11 and 12 each have an outwardly curved clamping edge 34.

The operation of my improved clip is shown in connection with cross-sectional Fig. 2. A section

45 of the hair to be waved is wound about a suitable mandrel 35. When the hair is thus wound it forms curl 36. A heating pad 37 is wrapped about mandrel 35, and encloses hair curl 36. Heating pad 37 carries heating material, such

50 as an exothermic powder. The exothermic powder produces heat when a chemical reaction is initiated, as is well known. However, an electrical heating pad may instead be used. A waterproof laminated wrapper 38 encloses heating

55 pad 37. The interior thereof is lined with ab-

sorbent material to absorb moisture which develops. The scalp is protected by scalp protector 40 which may have an appropriate construction well known to those skilled in the art.

After the hair has been curled about mandrel 35, and the heating pad 37 and laminated wrapper 38 have been applied, the clip is clamped thereabout. By manually compressing finger plates 15 and 16 against W-spring 32, jaws 11 and 12 are opened for slipping over wrapper 38. The free ends 34, 34 of the pivoted jaws 11, 12 which have a relatively short leverage, produce a relatively large force at the neck 39 of curl 36 and ends of pad 37 and wrapper 38. Such pressure affords a stable assembly of the system during operation and use, preventing dislocation of the hair with respect to the other elements. Springs 24, 26 operate independently of the W spring 32 and cause a continuous even pressure about the cylindrically held pad 37 and wrapper 38 through the coaction of central bridge member 10 and outer jaws 11, 12.

A modification of the clip of the invention is shown in Figs. 5 and 6. The W-shaped flat spring 32 of the previous embodiment is replaced by U-shaped flat spring 45. Spring 45 has the same action as W-shaped spring 32 described hereinabove. U-shaped spring 45 is secured to finger plates 15 and 16 by rivets 33, 33. The hair clip of Figs. 5 and 6 functions in the same manner, and generally is of the same construction described hereinabove.

Various changes and modifications may be made to the details of construction of the invention without departing from the broader spirit and scope thereof, as set forth in the following claims.

What I claim is:

1. A clip for a hair waving device comprising a center bridge member of substantial width, two arcuate side members hingedly connected

5 along opposite ends of said bridge member, the free ends of said side members being curved, springs pressing said free ends towards each other, a grip extending from each side member, and a flat spring connecting said grips in a manner to partly counteract the action of said springs to prevent complete collapse of said jaws when not in use.

10 2. In a device of the character described, a clip comprising a center bridge of substantial width, two arcuate jaws hingedly connected along opposite ends of said bridge, a coil spring between each of said jaws and bridge urging the free ends of said jaws towards each other, 15 a handle connected with each one of said jaws, and a flat spring joined between said handles in a manner to partly counteract the action of said coil springs to prevent complete collapse of said jaws when not in use.

15 3. A hair clip comprising a center bridge, two arcuate jaws pivotally connected along opposite ends of said center bridge, a coil spring on each of said jaws pressing the free jaw ends towards each other, opposed handles extending from said side member, and a W-shaped flat spring connecting said two handles in a manner to partly counteract the action of said springs to prevent collapse of said jaws when not in use.

20 4. A hair clip comprising a center bridge of substantial width, two arcuate jaws hingedly on said center bridge; the free ends of said side members being curved, a coil spring on each of said jaws pressing said free ends towards each other, a handle mounted on each of said side members, and a U-shaped flat spring connected 25 between said two handles in a manner to partly counteract the action of said coil springs to prevent collapse of said jaws when not in use.

HERMAN C. SCHLICKER.
